L. J. BETTS

TRAFFIC MARKER

Filed Aug. 25. 1922

UNITED STATES PATENT OFFICE.

LOUIS J. BETTS, OF WARREN, PENNSYLVANIA.

TRAFFIC MARKER.

Application filed August 25, 1922. Serial No. 584,301.

To all whom it may concern:

Be it known that I, LOUIS J. BETTS, a citizen of the United States, residing at Warren, in the county of Warren and State 5 of Pennsylvania, have invented new and useful Improvements in Traffic Markers, of which the following is a specification.

This invention relates to traffic markers such as are placed at street intersections to 10 designate by their presence turning points for vehicular traffic and has for its principal object the provision of a device of the character designated which may be easily and quickly removed and replaced leaving 15 the surface of the street or roadway smooth for traffic.

Another object of the invention is the construction of a traffic marker having an anchor block adapted to be embedded in the 20 ground and to be flush with the surface of the roadway when the traffic marker is removed therefrom, said traffic marker and anchor block having cooperating locking means whereby said marker is detachably 25 secured to the anchor block.

Still another object of the invention is the provision of a two-part traffic marker having a base detachably locked to the anchor block by means accessible from within said 30 base, and a cover for said base housing said locking means and detachably secured to the base by latching means carried entirely within said base and cover.

A further object of the invention resides 35 in the novel means by which the cover of the traffic marker is secured to the base.

With the above and other objects in view, my invention consists in the improved traffic 40 marker illustrated in the accompanying drawings, described in the following specification, and particularly claimed, and in such variations and modifications thereof as will be obvious to those skilled in the art to which my invention relates.

In the drawings accompanying and forming a part of this specification, and wherein the preferred embodiment of my invention 45 is illustrated:—

Figure 1 is a cross section of my improved 50 traffic marker.

Figure 2 is a plan view, parts being broken away.

Figure 3 is a plan view of the anchor 55 block.

Figure 4 is a detail in cross section showing one of the attaching lugs of the cover.

Figure 5 is a detail view in section showing the other of the attaching lugs about to be passed through the recess in the base.

Figure 6 is a side view partly in section 60 showing the latching means held in released position by a tool.

Figure 7 is a section on the line 7—7 of Figure 1 showing the latching means in latched position.

Referring now in detail to the several figures the numeral 1 represents portions of a paved roadway having one of the paving blocks removed therefrom forming a hole 2 which is filled with concrete and in which 70 the anchor block 3 is embedded. Said anchor block is constituted by a hollow casting having apertures 4 through the opposite walls thereof into which the concrete is forced by pressing the anchor block into the 75 concrete filled hole, forming a key by means of which the anchor block is irremovably located. The top surface of the anchor block is made flush with the surface of the paved roadway and is cast with a rectangular depression 5 a part of which is overhung 80 by the inwardly extending flange 6.

The marker comprises two parts, a base 7 and a cover 8. The base 7 is in the form of the segment of a cone and is provided with 85 a pair of diametrically disposed webs 9 and 10, formed at their point of intersection with a hollow hub 11 through which passes the bolt 12. The base of the marker is positioned by placing the head 13 of the bolt in 90 the rectangular depression 5 and then sliding the bolt until the head of the bolt engages beneath the overhanging flange 6. The base is then placed over bolt 12 which is passed thru hollow hub 11 and is then 95 lowered into position. The projecting portion 14 of the web 10 will then slide into the rectangular depression 5, the function of said projecting portion serving to retain the bolt beneath said overhanging 100 flange. A nut 15 is threaded on the upper end of the bolt 12, which when tightened against the upper end of the hub 11 holds the base 7 of the marker firmly against the anchor block and roadway. The projection 14 not only prevents the head of the bolt 12 from being slid from beneath the flange 6 but also keeps the base of the marker from 105 rotating.

In order to prevent unauthorized removal 110 or displacement of the marker through tampering with the nut 15 the cover 8 is pro-

vided having the form of the segment of a sphere and fitting the base 7 so that when the two parts of the marker are placed together the surface thereof will be of smooth 5 and continuous curvature. The cover 8 is provided with a pair of lugs 16 and 17 arranged at diametrically opposite points, and the base 7 is provided with a slot 18 for permitting the passage therethrough of one 10 of these lugs. The cover is put in place by first tilting it so that the lug 17 may engage beneath the inner edge of the base 7 as clearly shown in Figure 4. The cover is then lowered to a horizontal position until 15 the lug 16 passes through the slot 18, as shown in Figure 5. A lug 28 projects inwardly from the base adjacent the slot 18. The cover is then given a slight rotation so that the lug 16 passes out of registry with 20 the slot 18 and engages the inner wall of the base 7 adjacent said slot. The lug 28 makes it necessary to turn the cover in the right direction. As will be observed from Figure 2 the lugs 16 and 17 and the slot 18 are so 25 positioned that after an angular movement of the cover amounting to but a few degrees the lugs 16 and 17 abut against the web 9 making further rotation of the cover in one direction impossible.

30 In order to prevent rotation of the cover to the left after it has been moved to its extreme position in a clockwise direction as shown in Figure 2, latching means are provided consisting of a bar 19, which is pivotally mounted upon the web 10 by means of the pivot bolt 20. This bolt passes through the bar 19 closer to one end of the latter than the other so that the bar is out of balance, the inner end 21 being the heavier and 35 causing the bar to normally assume a position in which the outer end 22 projects above the plane of separation between the base and cover.

40 The cover 8 is provided with a lug 23, shown in Figures 1, 2 and 7 so positioned that when the lug 16 falls into the slot 18 the lug 23 will descend upon the outer end of the bar 19 depressing the same to a substantially horizontal position as shown in Figure 6. The lug 23 is also made of such 45 width that it remains in engagement with the outer end of the bar 19 from the time when the lug 16 enters the slot 18 until it is displaced to its extreme position in abutment with the web 9. At this point, however, the lug 23 terminates in an abrupt vertical shoulder permitting the outer end of the bar 19 to rise adjacent said shoulder forming a barrier to the return movement 50 of said lug and cover. The cover is removed by inserting a small wire or rod 24 through an aperture 25 in the cover which lies above the outer end of the bar 19, by means of 55 which wire or rod the end of said bar may be depressed so as to clear the shoulder of

the lug 23. By means of a suitable tool inserted through the apertures 26 and 27, the cover may then be rotated counter-clockwise until the lug 16 abuts against lug 28 said lug 16 coming into registry with the depression 18, at which point the cover may be lifted. This gives access to the nut 15, by loosening which the base 7 may be detached from the anchor block and removed. 70 The depression 5 in the anchor block is 75 made deeper and wider than the head 13 of the bolt so that the presence of a small amount of dirt or other foreign matter within the depression will not interfere with the insertion of the bolt. This is an important 80 feature as it is often desirable to remove the traffic marker for a season, during which time the depression 5 will become clogged with dirt or road material which must be dug out before it is possible to replace the 85 traffic marker. It is comparatively easy to roughly clean out said depression while it would be a laborious and time consuming 90 undertaking were it necessary to clean it out perfectly.

95 By means of the above described construction it is possible to anchor the traffic marker in such manner as to prevent its displacement either by lifting, sliding or rotation, and to so house and conceal the locking means as to render them inaccessible to any but authorized parties. Moreover, the latching means being entirely carried within the marker is protected from damage by traffic or by exposure to weather. When the traffic marker is removed the street is left 100 smooth and without any projection or other feature which would be detrimental to the safety or convenience of traffic.

Having described my invention what I 105 claim as new and desire to secure by Letters Patent, is:—

1. In combination, a traffic marker, an anchor block formed in its upper face with a recess bounded by an undercut portion, 110 said marker being provided with means for entering and obstructing the unoccupied part of said recess when the locking means is within said undercut portion.

2. In combination, a traffic marker and an anchor block, said anchor block being adapted to be positioned flush with the surface of a roadway and being provided in its upper face with a recess bounded by an undercut portion adjacent one end, a bolt carried by 115 said traffic marker having a head adapted to enter said recess and pass into said undercut portion and means engageable with said traffic marker for clampably holding said bolt against said flange.

3. In combination, a traffic marker and an anchor block, said anchor block being adapted to be positioned flush with the surface of a roadway and being provided in its upper face with a recess bounded by an under- 120 125

- cut portion, a bolt for said traffic marker having a head adapted to enter said recess and pass beneath said undercut portion, said recess being of greater dimensions than said head, and means engageable with said traffic marker for clamping said bolt against said flange.
4. In combination, an anchor block and a two-part traffic marker including a base portion provided with means for securing the same to said anchor block and a cover detachably latched to said base and housing said securing means.
5. In combination, an anchor block, a traffic marker, securing means for said traffic marker engageable with said anchor block, said traffic marker and anchor block being formed with interengaging means cooperating with said securing means to prevent dis- placement of the latter by lifting, sliding or by rotation.
6. In combination, an anchor block formed with a recess in its upper surface fully open at one end and having a narrowed opening at the other end bounded by an overhanging flange, a traffic marker provided with a transverse web, a bolt passing through said web, said bolt having a head adapted to enter the wide portion of said recess and slideable beneath said flange, said web being provided with a projection obstructing the wide portion of said recess when the traffic marker is in place and means cooperable with said web and with said bolt for detachably clamping said traffic marker to said anchor block.
7. A traffic marker comprising a base, means for detachably securing said base to an anchor block, and a cover detachably secured to said base and housing said securing means.
8. A two-part traffic marker comprising a base, means carried within said base for securing said traffic marker to an anchor block, a cover for said base housing said securing means and cooperating means carried within said base and cover for detachably latching said cover in position.
9. A two-part traffic marker comprising a base, having a circular opening at the top, means within said base for securing it to an anchor block, a rotatable cover fitting the circular opening in said base, said base being provided with a slot at the edge of said circular opening, said cover being provided with spaced lugs, one of said lugs being passable through said slot, said cover being secured in place by rotating the same to cause said lug to engage the inner wall of base at one side of said slot.
10. A two-part traffic marker, comprising a hollow base having conical inner and outer walls and provided with a circular opening in the top, means carried within said base for securing it to an anchor block, said se-
- curing means being accessible through said circular opening, a cover fitting said circular opening, and latching means carried within said base and cover comprising a recess formed in the wall of said circular opening and a lug carried by said cover passable through said recess and engageable with the inner wall of said base when rotated to one side of said recess, rigid means with which said lug engages to limit the rotation of said cover in one direction and a latch engageable with said cover when the limit of rotation in said direction is reached to prevent rotation in the other direction.
11. A two-part traffic marker, comprising a hollow base having conical inner and outer walls and provided with a circular opening in the top, means carried within said base for securing it to an anchor block, said securing means being accessible through said circular opening, a cover fitting said circular opening, and means for securing said cover to said base carried within said base and cover, comprising a recess formed in the wall of said circular opening and a lug carried by said cover passable through said recess and engageable with the inner wall of said base when rotated to one side of said recess, rigid means with which said lug engages to limit the rotation of said cover in one direction and a latch comprising a weighted swinging member having an end engageable with a projection on said cover when the latter has reached its limit of rotation in one direction to prevent its rotation in the other.
12. A two-part traffic marker comprising a hollow base having conical inner and outer walls and provided with a circular opening in the top, means carried within said base for securing it to an anchor block, said securing means being accessible through said circular opening a cover fitting said circular opening, means for securing said cover to said base carried within said base and cover, comprising a recess formed in the wall of said circular opening and a lug carried by said cover passable through said recess and engageable with the inner wall of said base when rotated to one side of said recess, rigid means with which said lug engages to limit the rotation of said cover in one direction and a latch comprising a weighted swinging member having an end engageable with a projection on said cover when the latter has reached its limit of rotation in one direction to prevent its rotation in the other, said cover being provided with means giving access to said latch for releasing it.
13. A two-part traffic marker comprising a hollow base having conical inner and outer walls and provided with a circular opening in the top, means carried within said base for securing it to an anchor block, said securing means being accessible through said

circular opening, a cover fitting said circular opening, means for securing said cover to said base carried within said base and cover, comprising a recess formed in the wall 6 of said circular opening and a lug carried by said cover passable through said recess and engageable with the inner wall of said base when rotated to one side of said recess, rigid means with which said lug engages to limit 10 the rotation of said cover in one direction and a latch comprising a weighted swinging member having an end depressable by a pro-

jection on said cover when said lug is passed through said recess and engageable with the end of said projection when the cover has 15 reached its limit of rotation in one direction to prevent its rotation in the other.

In testimony whereof I have hereunto set my hand in presence of two subscribing witnesses.

LOUIS J. BETTS.
